UNITED STATES PATENT OFFICE.

LOUIS G. MILLER AND EDWARD C. LONG, OF WESTMONT BOROUGH, PENNSYLVANIA.

REINFORCING AND HINGE PLATE FOR CARS.

1,251,683.

Specification of Letters Patent.

Patented Jan. 1, 1918.

Application filed September 4, 1917. Serial No. 189,479.

To all whom it may concern:

Be it known that we, LOUIS G. MILLER and EDWARD C. LONG, citizens of the United States, and residents of the Borough of 5 Westmont, in the county of Cambria and State of Pennsylvania, whose post-office addresses are Johnstown, Pennsylvania, have invented certain new and useful Improvements in Reinforcing and Hinge Plates 10 for Cars; and we do hereby declare the following to be a full, clear, and exact description of the invention, such as will enable others skilled in the art to which it appertains to make and use the same.

15 Our invention relates to the construction of hoppers used around the discharging openings of cars and particularly in those cars made of steel or other metal, and has for its object to provide a member which, by reason 20 of its design and construction, combines several functions in one structure, thereby conducing to lightness, economy of labor and material and efficiency for the purpose intended.

25 Our invention relates generally to strengthening the lower edge portion of the material surrounding the discharge openings of hopper bottom cars, the metal plate material of which is made as light as possible, but which, 30 on account of the door hinges secured thereto and the loads and shocks which this portion has to carry, should be reinforced to prevent failure or deformation. We accomplish our purpose by applying to or near the 35 lower edge of the hopper sheet of a car, or the floor sheet of a gondola car, a reinforcing plate and hinge combined, which at once serves two purposes and all portions aid the other parts in strengthening the structure, 40 which is not the case in prior constructions of this kind.

Having thus given a general description of our invention, we will now, in order to make the matter more clear, refer to the annexed sheet of drawings, which forms part 45 of this specification and in which like characters refer to like parts; Figure 1 is a vertical longitudinal sectional elevation through the hopper and doors of a portion of a car 50 taken on the line III—III of Fig. 2; Fig. 2 is a vertical transverse sectional elevation taken on the line II—II of Fig. 1; Fig. 3 is an enlarged detail sectional elevation of a portion of the hopper and door taken on 55 the line III—III of Fig. 2; Fig. 4 is a top plan view of our combined reinforcing hinge

plate; Fig. 5 is a side elevation of our combined reinforcing hinge plate, the door hinges being shown in section; and Fig. 6 is an end elevation of our combined reinforcing hinge plates.

Referring now to the characters of reference on the drawings:—1 is that portion of the car in general including the hopper and door, 2 are the side hopper sheets thereof, 3 is the central ridge, 4 and 5 are the transverse hopper sheets, 6 is our reinforcing hinge plate in general, all parts of which are formed integral and which may be a steel or malleable iron casting, which 60 is provided with openings 7 for the purpose of lightening the construction thereof, 8 is the forward flanged edge of the hinge plate which projects downwardly, as shown, along the lower edge of the same, 9 is the rear 65 flanged edge of the hinge plate, which, as illustrated, is deeper in the middle than at the ends and projects downwardly for a considerable distance in order to make a strong girder structure, 10 are transverse 70 ribs extending from the rear flange to the forward flange and projecting downwardly, these ribs being provided with bosses 11 and also being provided with holes 13 there- 75 through, while 12 are the door hinges which 80 are the usual strap hinges, one end of which is bent and surrounds the hinge pin 14 while their other ends are riveted to the door 15, as illustrated.

It should be noted that the forward flange 80 8 is of considerably less depth than the rear flange 9 in order to provide ample clearance for the door which is adjacent to the forward flange. The rear flange 9, which is removed from the door flanges, is made 95 quite deep and of fish-bellied construction to provide strength and stiffness to the structure. The flanges 8 and 9 may also extend around the ends of the plate as illustrated.

100 Our hinged reinforcing plate is firmly riveted or bolted to or near the lower edge of the hopper or floor plates 4 and 5, as illustrated, and serves to strengthen and stiffen the same while at the same time providing integral hinges on which the door 15 may swing.

105 It should be noted that the portion of the hinge plate adjacent the hinges is wider than the intermediate or end portions in 110 order to provide means for firmly securing same to the floor sheet at these points and

also to strengthen the structure at this location, where the stresses are greatest.

Although we have shown and described our invention in considerable detail, we do not wish to be limited to the exact details of construction specified, but we may use such substitutions, modifications or equivalents thereof as are embraced within the scope of our invention as pointed out in the 10 claims.

Having thus described our invention, what we claim and desire to secure by Letters Patent is:—

1. The combination with the floor sheet 15 of a car, of a reinforcing hinge plate secured near the edge thereof, said plate being provided with a flat portion contiguous to said floor sheet with downwardly projecting flanges on the longitudinal edges thereof, 20 and transversely extending ribs provided with openings therein adapted to receive the hinge pin.

2. The combination with a floor sheet of a car, of a reinforcing hinge plate secured 25 near the edge thereof, comprising a flat portion contiguous to the lower side of said plate, downwardly extending flange portions extending longitudinally thereof, the flange farthest removed from the door being deeper

than the other, and means formed integral 30 with said plate for mounting the hinge pin thereon.

3. The combination with a metal car, of a combined reinforcing and hinge plate secured thereto, said plate comprising a flat 35 portion adjacent to the underside of the car floor, downwardly projecting flanges longitudinally extending from the edges thereof, transverse ribs extending downwardly from the plate portion and provided with registering openings therein, adapted to receive the hinge pins.

4. A combined reinforcing and hinge plate for cars, comprising a flat portion arranged contiguous to the lower side of the car bottom adjacent to the discharge opening thereof, said plate being provided with downwardly projecting flanges extending around the edges thereof, a pair of transverse downwardly extending ribs spaced apart 50 and provided with registering holes therethrough near each end of said plate, the portions of said plate adjacent said ribs being wider than the other portions.

In witness whereof we hereunto affix our 55 signatures.

LOUIS G. MILLER.
EDWARD C. LONG.
